UNITED STATES PATENT OFFICE

1,991,072

PARALLEL RODLINE POWER TRANSMITTING CONNECTERS

William R. Barney, Fort Worth, Tex.

Application February 8, 1934, Serial No. 710,286

4 Claims. (Cl. 74—110)

My invention relates to new and useful improvements in means of changing the pull on a rodline for operating a pump jack from one directional line to another directional line parallel thereto, and has for its primary object the provision of such a device for use in underground rodline crossings, as of roads, where the use of holdups and holddowns would be awkward to install or use or for any other reason would be undesirable, and in general to provide a practical means of abruptly avoiding a building, foundation, tank or other obstruction. Another object is to provide such a device in manner adapted to deflect the pull of the rodline at an angle.

With the above and other objects in view which will be disclosed as the description proceeds, my invention consists in the novel features herein-after set forth, shown in the accompanying drawing and more particularly pointed out in the appended claims.

Referring to the drawing in which like numerals represent similar parts thruout the several views:

Fig. 1 is a top plan view of my device mounted on the walls of a concrete pit and shown as in use in making an underground rodline crossing beneath a roadway.

Fig. 2 is a view of the same in side elevation on line A—A of Fig. 1.

Fig. 3 is a view of the same in end elevation on line B—B of Figs. 1 and 2.

Fig. 4 is a view in side elevation of my front truck axle housing and connecting lugs thereon.

Fig. 5 is a view in side elevation of my rear truck axle housing and connecting lugs thereon and with the carriage arm thereto connected.

Fig. 6 is a view of the same in end elevation.

Fig. 7 is a view in side elevation of my link mounted at the end of the carriage arm and having the tension coupler of the carriage connected thereto and also having a rodline connection thereon.

Fig. 8 is a cross sectional diagrammatic view of a rodline installation at an underground road crossing, wherein my device is employed at both sides of the road as a combined holdup and hold-down in both instances.

Fig. 9 is a top plan diagrammatic view of a rodline installation using my device for abruptly avoiding obstructions such as a building and a tank.

In Figs. 1, 2, 3 and 8, numeral 1 represents the side walls of a pit 2 wherein my device is positioned at a roadway which is ditched at both

sides as at 3 and has a roadbed thereon as indicated at 4, with an underground tunnel for a rodline, said tunnel being a pipe 5. In Fig. 9, numeral 6 represents a pier foundation support for said device, with 7 indicating a building and 8 a tank, both of which are obstructions to be abruptly avoided by the rodline into which my device is connected.

Turning to the device itself, the preferred form of which is disclosed in the drawing, 9 represents tracks of structural steel I beams arranged in pairs on which the carriage of my device may travel with the reciprocating motion imparted to it by the movement of the rodline to which it may be connected.

The carriage aforesaid is made with a front truck indicated generally by 10 and a rear truck indicated generally by 11, connected by two couplers hereinafter mentioned.

The front truck 10 comprises wheels 12 on an axle 13 held in a housing 14 having a bore 15 therein to receive said axle, and with said housing having a lug 16 thereon adapted to receive a rodline connection 17 pivotally secured thereto thru a pin aperture 18, and having another lug 19 thereon adapted to receive the two couplers between said trucks, one being a strut or compression coupler member 20 pivotally secured to said lug 19 thru a pin aperture 21, and the other being a stay or tension coupler member 22 pivotally secured to said lug 19 thru a pin aperture 23.

The rear truck 11 comprises wheels 24 on an axle 25 held in a housing 26 having a bore 27 therein to receive said axle, and with said housing having a lug 28 thereon adapted to receive compression coupler 20 which is pivotally secured thereto thru a pin aperture 29, and having another lug 30 thereon whereto the hereinafter mentioned spreader arm or carriage arm, which is indicated generally by 31, may be secured to said truck 11 thru a pin or bolt 32.

The aforesaid spreader arm 31 is shown as composed of two structural steel channel irons 33 bolted to truck 11 at one end and mounting a pin or shaft 34 at the other end, on which shaft is pivotally mounted a link 35 adapted to pivotally secure the tension coupler 22 thereto by means of a pin 36, and also adapted to pivotally secure a rodline connection 37 thereto by means of the pin 38.

The rodline is operatively connected with the device at both tension ends thereof, that part of the rodline connected with rodline connection 17 being designated as a rodline 39 and that part

of the rodline connected with the rodline connection 37 being designated as a rodline 40, this part of the rodline being attached to carriage arm 31 as shown, whereby the rodline is abruptly staggered out of line with the direction of rodline 39. If it is desired to abruptly return the rodline into its original line, another of my devices may be employed as illustrated. If the angle of the pull is also to be changed, as if it should be desired to continue the rodline 40 in a direction as indicated by dotted line 41 of Fig. 9, assuming that rodline 39 is connected to the power and rodline 40 is connected to the load, this may be done in as much as rodline 40 is pivotally connected to my carriage.

Figs. 1, 2 and 8 of the drawing illustrate the rodline 40 as being run in pipe 5 under the roadway, and in Fig. 8 the line is shown as again returned as line 42 to the surface thru the use of a second of my devices placed on the opposite side of the road.

Fig. 9 illustrates the use of my device in making an abrupt horizontal change in the direction of the rodline as if to avoid obstructions such as the building and tank indicated.

In operation, with the device in place and the rodline connected to the power and to its load, the carriage will travel on the tracks and transmit the power between rodlines 39 and 40, in manner heretofore explained.

Having thus fully disclosed my invention, what I claim and desire to secure by Letters Patent is:

1. In a rodline power transmitting member, a carriage, a rodline connection thereto, means of restricting the movement of said carriage to a substantially straight line, a spreader arm on said carriage, and a rodline connection to said arm, and with said last mentioned connection offset to and out of line with said first mentioned connection.

2. In a rodline power transmitting member as claimed in claim one, and wherein said rodline connection to said arm is pivotal.

3. A rodline power transmitting member adapted to be connected into a rodline, and with said member comprising a pair of trucks each having a pair of wheels thereon, a track for said wheels, a compression coupler connecting said trucks together, a spreader arm on one of said trucks, a tension coupler connecting the other of said trucks with said spreader arm, a rodline connection to the truck wherewith said tension coupler is directly connected as aforesaid, and another rodline connection to said spreader arm.

4. A rodline power transmitting member as claimed in claim three, and wherein said last named rodline connection is pivotal.

WILLIAM R. BARNEY.
